UNITED STATES PATENT OFFICE.

WILLOUGHBY D. KELLEY, OF CLEVELAND, OKLAHOMA TERRITORY,
ASSIGNOR OF ONE-FOURTH TO JOSEPH ALDERSON, OF CLEVE-
LAND, OKLAHOMA TERRITORY.

BALING-PRESS.

SPECIFICATION forming part of Letters Patent No. 789,369, dated May 9, 1905.

Application filed May 26, 1904. Serial No. 209,908.

To all whom it may concern:

Be it known that I, WILLOUGHBY D. KELLEY, a citizen of the United States, residing at Cleveland, in the county of Pawnee, Oklahoma Territory, have invented a new and useful Baling-Press, of which the following is a specification.

This invention relates to baling-presses for hay, cotton, and similar material, and has for its object to simplify and improve the construction and produce an apparatus of this character wherein the material may be handled with greater facility and in less time than in presses as heretofore constructed and without increase in the power required.

With these and other objects in view, which will appear as the nature of the invention is better understood, the same consists in certain novel features of construction, as hereinafter fully described and claimed.

In the accompanying drawings, forming a part of this specification, and in which corresponding parts are denoted by like designating characters, is illustrated the preferred form of the embodiment of the invention capable of carrying the same into practical operation, it being understood that the invention is not necessarily limited thereto, as various changes in the shape, proportions, and general assemblage of the parts may be resorted to without departing from the principle of the invention or sacrificing any of its advantages, and the right is therefore reserved of making all the changes and modifications which fairly fall within the scope of the invention and the claims made therefor.

In the drawings thus employed, Figure 1 is a side elevation, partly in section, and Fig. 2 is a plan view of the improved apparatus. Fig. 3 is a plan view with the feed-hoppers and cut-off plates removed. Fig. 4 is a longitudinal section on the line 4-4 of Fig. 1 looking upward. Fig. 5 is a transverse section on the line 5-5 of Fig. 1. Fig. 6 is an end elevation partly in section. Fig. 7 is a view of one of the feed-hoppers detached and folded.

The press-box is formed of the usual size in transverse section and of the usual length

and preferably with two compression-chamber portions 10 11 spaced apart and with a guide-frame 12 between them. The bale-receiving portions of the press-box may be extended to any desired length and formed with closed tops 13 and bottoms 14, leaving the sides open and disconnected at the terminals. The usual timber-work inclosing frame 15 is employed to support the press-box, and between the terminals of the top portions 13 and the end members of the frame 15 springs are disposed, one of which is represented at 16, and exerting their force to maintain the terminals yieldably contracted, so that the bales will be retarded at the discharge end to facilitate the action and prevent premature discharge of the bales. Adjusting-screws 17 are disposed in the end members of the frame 15 for bearing upon the springs to regulate the tension.

Mounted for reciprocal movement in the compression-chamber portions 10 11 are plungers 18 19, connected by a rack-bar 20, extending through the guide-frame 12 and of proper length to cause the plungers to operate alternately. Pivoted at 21 in bearings 22 is a segmental gear 23, engaging the rack-bar 20 and with a socket 24 for an operating lever 75 or sweep 25, by means of which the plungers may be alternately reciprocated in the compression-chamber portions.

Attached longitudinally to the upper edges of the press-box opposite the compression-chamber portions of the same are guide members 26 27, connected by spaced transverse stay-bars 28, forming supports for feed-hoppers 29 30, through which the material is fed to the compression-chamber portions and preferably arranged in reverse order, so that the material may be fed thereto alternately from opposite sides. The hoppers are detachable from their supporting-frames and formed with three inclined sides hinged together at the 90 ends, as at 31 32, so that they may be folded into a small compass when detached for removal or storage, as shown in Fig. 7.

The upper edges of the side walls of the compression-chamber portions of the press-box are recessed to receive cut-off plates 33 34,

the plates being further supported from above by the longitudinal frame members 26 27. By this means the cut-off plates are disposed for reciprocal movement between the feed- 5 hoppers and the compression-chamber portions of the press-box and the plungers operative therein.

Connected to the back of each of the plungers 18 19 are cable-guide pulleys 35 36, over 10 which cables 37 38 lead, and are connected at one end, respectively, as at 39 40, to the adjacent ends of the cut-off plates 33 34 and at their other ends to springs 41 42, the latter connected in turn to opposite sides of the guide- 15 frame 12, as at 43 44.

A spring 45 is connected at one end, 46, to the cut-off plate 34 and at the other end, 47, to the rear side of the plunger 18, and a like spring 48 is connected at one end, 49, to 20 the cut-off plate 33 and at the other end, 50, to the rear side of the plunger 19. By this arrangement as the segmental gear 23 is operated in one direction the plunger 19 will be moved forwardly in the compression-chamber 25 portion 11 and the plunger 18 withdrawn from the chamber 10, and at the same time the cut-off plate 34 will be caused to travel in advance of the plunger 19 and close the discharge from the hopper 30 before the plunger completes 30 its forward stroke, and the cut-off plate 33 will likewise be caused to travel rearwardly and open the discharge from the hopper 29. Each of the cables 37 38 is shorter than the full stroke of the respective plunger with 35 which it is associated, so that during the forward stroke the cut-off plates will move faster than the plungers and in advance of the same, and thus serve as stops to hold down the material which is being compressed and prevent 40 it from rising during the pressing action. As the cut-off plates reach the end of the strokes before the completion of the forward strokes of the plungers, the springs 41 42 by expanding permit the continued forward 45 movement of the plungers, as will be obvious, until the stroke is completed. Each forward stroke also expands the secondary springs 45 48, which by their reaction draw the cut-off plates backward and reopen the 50 discharge-apertures of the hoppers alternately, as will be obvious.

The contraction of the discharge ends of the press-boxes are also important features of the invention and add materially to the value and 55 increase the efficiency of the invention.

The open-sided press-boxes provide easy access to the compressed bales to readily apply the binding-wires, as will be obvious.

Spring-controlled detents 51 52 are disposed 60 at suitable points to hold the material after each compression, each pair of detents being held by a single spring, as at 53 54.

Having thus described my invention, what is claimed is—

65 1. In a baling-press, a cut-off plate, and

means for moving the same in the same direction, but at a greater speed than the plunger of the press.

2. In a baling-press, a plunger, a cut-off plate connected thereto, and means for traveling the cut-off plate at a greater speed than the plunger. 70

3. In a baling-press, the press-box having a feed-hopper disposed above the compression-chamber portion of the same, a plunger mounted for reciprocation in said compression-chamber portion, a cut-off plate movable between said plunger and hopper, and means whereby said cut-off plate is operated in advance of the plunger during the forward stroke. 75

4. In a baling-press, the press-box having a feed-hopper disposed above the compression-chamber portion of the same, a plunger mounted for reciprocation in said compression-chamber portion, a cut-off plate movable between said plunger and hopper, means whereby said cut-off plate is operated in advance of the plunger during the forward stroke, and means whereby the cut-off plate is withdrawn from between the hopper and compression-chamber 90 at the return stroke.

5. In a baling-press, the press-box having a feed-hopper disposed above the compression-chamber portion of the same, a plunger mounted for reciprocation in said compression-chamber portion, a cut-off plate movable between said plunger and hopper, a cable-guide carried by said plunger, a spring connected to the wall or frame of said compression-chamber, and a cable connected between said spring 100 and cut-off plate and leading through said guide. 95

6. In a baling-press, the press-box having a feed-hopper disposed above the compression-chamber portion of the same, a plunger mounted for reciprocation in said compression-chamber portion and provided with a rearwardly-extending rack-bar, a segmental gear member mounted for oscillation in said press-box frame and engaging said rack-bar, a cut-off plate movable between said hopper and plunger, and means connected between said cut-off plate and plunger to cause said plate to be projected in advance of the plunger during the forward stroke and withdrawn during the 110 return stroke. 105

7. In a baling-press two press-boxes disposed in longitudinal alignment and having a transverse guide-frame between the respective compression-chamber portions of the same, reversely-disposed feed-hoppers independently positioned above said compression-chamber portions, plungers operating in said compression-chamber portions and connected for alternate reciprocation therein by a rack-bar extending through said guide-frame, a segmental gear mounted for oscillation in said press-box and engaging said rack-bar for alternately operating said plungers, cut-off plates movable between said hoppers and said 115 120 125 130

compression - chamber portions, and means connected between said cut-off plate and plunger for causing said plates to be alternately reciprocated in advance of said respective plunger during the forward stroke.

8. In a baling-press, two press-boxes disposed in longitudinal alinement and having a transverse guide-frame between the respective compression - chamber portions of the same, reversely-disposed feed-hoppers independently positioned above said compression-chamber portions, plungers operating in said compression-chamber portions and connected for alternate reciprocation therein by a rack-bar extending through said guide-frame, a segmental gear mounted for oscillation in said press-box and engaging said rack-bar for alternately operating said plungers, cut-off plates movable between said hoppers and said compression-chamber portions, cable-guides carried upon the rear sides of said plungers, oppositely-extending springs connected to said guide-frame and cables connected respectively between said springs and cut-off plates and leading through said guides, whereby said cut-off plates are caused to travel in advance of said plungers during the forward stroke.
- 25 9. In a baling-press, the press-box having

a feed-hopper disposed above the compression-chamber portion of the same, a plunger mounted for reciprocation in said compression-chamber portion, a cut-off plate movable between said plunger and hopper, a cable-guide carried by said plunger, a primary spring connected to the frame of said compression-chamber, a cable connected between said primary spring and cut-off plate and leading through said cable-guide, and a secondary spring connected to said cut-off plate and exerting its force reversely to the primary spring.

10. In a baling-press, the press-box having a compression-chamber at one end, a feed-hopper detachably supported above said compression-chamber portion and formed of side members hinged at the junctures to fold into small area when detached, a plunger for reciprocation in said compression-chamber, and a cut-off plate slidable between said hopper and compression-chamber.

In testimony that I claim the foregoing as my own I have hereto affixed my signature in the presence of two witnesses.
